UNITED STATES PATENT OFFICE

140,330

DESIGN FOR A REVERSIBLE APRON

Alice S. Baker, Lennox, Calif.

Application June 13, 1944, Serial No. 113,974

Term of patent 14 years

(Cl. D3—26)

To all whom it may concern:

Be it known that I, Alice S. Baker, a citizen of the United States, residing at Lennox, county of Los Angeles, in the State of California, have invented a new, original, and ornamental Design for a Reversible Apron, of which the following is a specification, reference being had to the appended drawing, forming part thereof.

Fig. 1 is a front view of a reversible apron showing my design.

Fig. 2 is a rear view thereof, with the tie sash shown broken away for purposes of illustration; and

Fig. 3 is an enlarged sectional view taken along the line 3—3 of Fig. 1.

The protective member depending from the waistband of the apron, as shown in Fig. 1, is suspended at the edges leaving a slot through which the bib portion may be drawn when the apron is reversed.

I claim:

The ornamental design for a reversible apron, substantially as shown and described.

ALICE S. BAKER.
